UNITED STATES PATENT OFFICE.

GEORGE E. DAY, OF CLEVELAND, OHIO, ASSIGNOR TO THE WELLMAN-SEAVIER-MORGAN COMPANY, OF CLEVELAND, OHIO, A CORPORATION OF OHIO.

ROLLING-MILL-OPERATING MECHANISM.

1,280,677.

Specification of Letters Patent.

Patented Oct. 8, 1918.

Application filed March 15, 1918. Serial No. 222,581.

To all whom it may concern:

Be it known that I, GEORGE E. DAY, a citizen of the United States, residing at Cleveland, in the county of Cuyahoga and State of Ohio, have invented a certain new and useful Improvement in Rolling-Mill-Operating Mechanism, of which the following is a full, clear, and exact description.

This invention is an improvement in the driving mechanism for a plurality of stands of alined rolls for rolling structural iron and the like. The object is to provide driving mechanism operable by a single motor by means of which all of the rolls may be driven when all are required, but whereby, when any stand of rolls is put out of commission for any reason, all of the other stands of rolls may be continued in operation.

The invention consists in the construction and combination of parts shown in the drawing, hereinafter described and definitely pointed out in the appended claims.

In the drawings, Figure 1 is a plan view, Fig. 2 is an elevation of a four-stand rolling mill equipped with this invention; and Fig. 3 is a vertical section through a pinion housing.

In the embodiment of the invention shown there are four three-high stands 10, 11, 12, 13, or rolls set side by side with the corresponding rolls of the four stands in substantial alinement. The corresponding, i. e., substantially alined rolls of the four stands, are operatively connected by coupling sleeves 14 and spindles 15 of well known construction.

Each of the two outside stands 10 and 13 is associated with a pinion housing 16. In each pinion housing are mounted three shafts 20, 21, 22, in substantial alinement with the three rolls in the adjacent stand, and each of these shafts is connected with the adjacent substantially alined roll by means of coupling sleeves 14 and a spindle 15 substantially as before explained.

Within the pinion housings are pinions 23 secured respectively to said shafts, and in mesh with each other. One of the three spindle shafts—it matters not which one—extends out of the housing and its projecting outer end is operatively connected with a gear, preferably by a spindle 15, and coupling sleeves 14, which engage with the

spindle and with the projecting pinion 55 shaft, and a shaft 31 which carries said gear 30. These two gears 30 respectively mesh with gears 32 and 33 fixed to the driving shaft 34 which extends transversely with respect to the stands of rolls, and 60 from one side of the group to the other. A single motor 35 is employed to drive this shaft.

Under normal conditions, that is to say, when all of the stands of rolls are capable 65 of being used, and the use thereof is desired, there is a dual driving connection, that is to say, the rolls are driven from both sides of the group through the gears 30, the pinions in the two pinion housings, and 70 the coupling sleeves and spindles. If, however, it is desired to cut out one stand of rolls either because it is not required for the work being done, or because something about it requires repairing, the rolls of 75 that stand are uncoupled from the rolls of the stands on opposite sides thereof, or from the rolls on one side and pinion shafts on the other. In that event, the remaining rolls will be driven by the described mechanism, that is to say, all of the rolls on one side of the so cut out stand will be driven from the pinion housing that side of the group, and all of the rolls on the opposite side of the cut out stand will be 80 driven through the pinion housing on the other side of the group. When it is desired to put into commission the stand of rolls temporarily in disuse one merely couples the ends of the rolls by the described 85 coupling mechanisms with the rolls on either side thereof.

Having described my invention, I claim:

1. In a multiple stand rolling mill, the combination of a plurality of stands of rolls 95 set side by side with the corresponding rolls of the several stands in substantial alinement, means for connecting and disconnecting the adjacent ends of the alined rolls, two pinion housings respectively located adjacent the outside stands of the group of stands of rolls, pinion shafts mounted in each pinion housing in substantial alinement with the adjacent rolls, coupling devices for connecting the adjacent ends of 100 said pinion shafts and alined rolls, intermeshing pinions secured to said pinion shafts, a single motor, a shaft driven there-

by, and driving connections between said shaft and the pinions in both pinion housings.

2. In a multiple stand rolling mill, the combination of a plurality of stands of rolls set side by side with the corresponding rolls of the several stands in substantial alinement, means for connecting and disconnecting the adjacent ends of the alined rolls, two pinion housings respectively located adjacent the outside stands of the group of stands of rolls, pinion shafts mounted in each pinion housing in substantial alinement with the adjacent rolls, coupling devices for connecting the adjacent ends of said pinion shafts and alined rolls, intermeshing pinions secured to said pinion shafts, and means by which to drive the pinions in both housings at the same rate.
3. In a multiple stand rolling mill, the combination of a plurality of stands of rolls set side by side with the corresponding rolls of the several stands in substantial alinement, means for connecting and disconnect-

ing the adjacent ends of alined rolls, two pinion housings respectively located adjacent the outside stands of the group of stands of rolls, pinion shafts mounted in each pinion housing in substantial alinement with the adjacent rolls, coupling devices for connecting said pinion shafts with the alined rolls, intermeshing pinions secured to said shafts, one of said shafts being projected out from each pinion housing, a gear coupled to the projecting end of each of said pinion shafts, and a single transversely extended driving shaft, gears thereon in constant mesh with the gears coupled to the projecting end of the pinion shafts, and a single motor for driving said driving shaft.

In testimony whereof, I hereunto affix my signature.

GEORGE E. DAY.
